(57) **CLAIM**

The ornamental design for a forklift truck, as shown and described.

DESCRIPTION

FIG. 1 is a front view of a forklift truck showing our new design;

FIG. 2 is a rear view thereof;

FIG. 3 is a top plan view thereof;

FIG. 4 is a bottom plan view thereof;

FIG. 5 is a right side view thereof;

FIG. 6 is a left side view thereof; and,

FIG. 7 is a front perspective view thereof.

The solid line indicates a portion to be registered as a partial design.

The broken lines on the figures are included for the purpose of illustrating environment and form no part of the claimed design.

1 Claim, 7 Drawing Sheets
